UNITED STATES PATENT OFFICE.

EUGENE L. HUSTING, OF MILWAUKEE, WISCONSIN.

DESIGN FOR A BOTTLE.

Application filed January 20, 1923. Serial No. 4,940. Term of patent 14 years.

To all whom it may concern:

Be it known that I, EUGENE L. HUSTING, a citizen of the United States, residing at Milwaukee, in the county of Milwaukee and State of Wisconsin, have invented a new, original, and ornamental Design for Bottles, of which the following is a specification, reference being had to the accompanying drawing, forming part thereof.

Fig. 2 is a bottom plan view of the bottle.
I claim:

The ornamental design for a bottle, as shown.

EUGENE L. HUSTING.
